DESIGN FOR A COMBINED FAUCET AND SOAP DISH

Albert G. Smolensky, Cleveland, Ohio

Application October 31, 1945, Serial No. 123,341

Term of patent 14 years

(Cl. D91—3)

To all whom it may concern:

Be it known that I, Albert G. Smolensky, a citizen of the United States, residing at Cleveland, in the county of Cuyahoga and State of Ohio, have invented a new, original, and ornamental Design for a Combined Faucet and Soap Dish, of which the following is a specification, reference being had to the accompanying drawing, forming part thereof.

Fig. 1 is a top plan view of a combined faucet and soap dish, showing my new design;

Fig. 2 is a front elevational view thereof; and

Fig. 3 is an end view thereof.

I claim:

The ornamental design for a combined faucet and soap dish, as shown.

ALBERT G. SMOLENSKY.
